UNITED STATES PATENT OFFICE.

RAY DAVIS, OF LEHIGH, IOWA.

NUT OR BOLT HOLDING DEVICE.

1,251,347.

Specification of Letters Patent. Patented Dec. 25, 1917.

Application filed April 10, 1917. Serial No. 161,034.

To all whom it may concern:

Be it known that I, RAY DAVIS, a citizen of the United States, residing at Lehigh, in the county of Webster and State of Iowa, have 5 invented new and useful Improvements in Nut or Bolt Holding Devices, of which the following is a specification.

This invention relates to means for engaging the head of a bolt or nut to permit of 10 the operation of a suitable construction such as a wrench to disconnect the bolt or nut.

The device is adapted for use upon the crank and transmission cases of automobiles which are constructed in two sections, the 15 meeting edges of which are flanged, the securing bolts and the nuts therefor passing through openings in the said flanges. The arrangement of the nuts and bolts is such that two wrenches are employed for removing 20 the nuts from or screwing the same upon the bolts, and therefore the necessity of the employment of both of the hands of a machinist, or the necessity of employing two machinists, one operating one of the wrenches 25 and the other holding the other wrench to prevent the turning of the bolt while the nut is being operated upon is necessitated. In the United States Patent No. 1,213,756 granted me on Jan. 23, 1917 I have produced 30 an instrument which will automatically engage with the head of one of the holding members while the operator employs a wrench for actuating the other holder member, either the nut or the bolt, the said device 35 including a socket member to receive the nut or the bolt and a clamping member to hold the said nut or bolt in the socket. I have discovered that this structure is, to a certain extent, defective, for the reason that 40 when the wrench is applied to turn one of the elements of the holding or securing members, the wrench when turning the other gripping or holding member either the nut or the bolt will cause the implement to turn 45 upon the nut or bolt and to contact with one of the sides of the automobile case. If the implement is not properly positioned, the force of contact will have a tendency to break or loosen the pivotal connection of the gripping 50 member with the socket and to bring the said gripping member out of proper alinement with the slot in the socket member through which the gripping member passes and it may, therefore, be considered the primary 55 object of the present invention to produce a nut wrench of this character which may be

readily placed upon a nut or bolt to engage therewith and which is provided with means whereby to contact with the casing of the automobile or the like to present a pivoted 60 gripping member associated with the instrument when being brought likewise into such contact with the case, so that danger of injury to the said pivoted gripping member will be obviated with this respect. 65

In the accompanying drawing:

Figure 1 is a view illustrating the application of the improvement,

Fig. 2 is a perspective view of the improved implement or tool, 70

Fig. 3 is a top plan view of the same, and

Fig. 4 is a detail sectional view approximately on the line 4—4 of Fig. 3. 75

In the drawing the numeral 1 designates a crank and transmission case of an automobile constructed in sections having meeting edges which are flanged outwardly and said flanges being provided with openings through which pass the connecting or securing bolts and the nuts therefor, and in Fig. 80 1 of the drawing the improvement is illustrated in engaging position with one of the nuts, while a spanner wrench is shown engaging the head of one of the bolts whereby to turn the bolt to release the same from 85 the nut.

The improvement is substantially similar to that illustrated in my said Patent No. 1,213,756, but in order to comprehensively set forth the advantages of the improvement 90 over the said patent it will be necessary for me to briefly refer to the construction as set forth in my said patent.

The implement or tool includes a socket member 2 having a handle member 3, and 95 the bore of the socket is of a size to snugly receive the nut. The socket is provided with a longitudinal slot or opening entering from the outer end thereof, and the said socket to the opposite sides of the opening and 100 upon the lower portion of the said socket or that portion adjacent its connection with the handle 3 is formed with outturned ears 4 through which is passed a pivot 5 that secures the jaw 6 of the gripping member 105 7 to the socket. The gripping member includes a handle 8 and interposed between the said handle 8 and the handle 3 is a helical spring 9 which normally forces the operating edge or face 10 of the gripping member to within the bore of the socket 2. 110 The operating face 10 is substantially V-

shaped, and the numeral 11 designates a stop member which is arranged upon the member 6 and designed to contact with the socket to limit the inward movement of the 5 jaw with respect to the bore of the socket.

My improvement resides in providing the socket with or forming thereon outwardly extending lugs 12-12 disposed to the opposite sides of the slot to which the jaw of the 10 gripping member passes and arranged at opposite angles with respect to the longitudinal plane of the socket. These lug members 12-12 are so positioned that one of the same will contact with the side or face of the crank case regardless of the position 15 upon which the improvement is arranged upon the nut and the said lugs 12 are designed to protect the gripping member from contact with the wall of the case and thus 20 inflict injury thereon.

Having thus described the invention, what I claim is:

In a device for the purpose set forth, the combination of a socket member provided with a handle and formed with an opening 25 communicating with its bore, the opening receiving the head of a spring pressed gripping member which is pivotally connected with the socket, of lugs formed upon the socket at the opposite sides of the opening 30 receiving the gripping member and disposed at opposite outward angles with respect to the said gripping member whereby to form obstructions to prevent contact with the gripping member when the socket member 35 is positioned upon or turned with an article engaged in the said socket member.

In testimony whereof I affix my signature.

RAY DAVIS.
